UNITED STATES PATENT OFFICE.

WILLIAM F. PAGEL, OF SYCAMORE, ILLINOIS.

INTERNAL-COMBUSTION ENGINE.

Application filed January 15, 1920. Serial No. 351,597.

To all whom it may concern:

Be it known that I, WILLIAM F. PAGEL, a citizen of the United States, residing at Sycamore, in the county of De Kalb and State 5 of Illinois, have invented a certain new and useful Improvement in Internal-Combustion Engines, of which the following is a full, clear, concise, and exact description, reference being had to the accompanying 10 drawings, forming a part of this specification.

My invention relates to improvements in internal combustion engines and has special reference to improvements in fuel feeding 15 and ignition means.

It is my object to provide improved means for priming the engine for starting it, which means shall serve to protect clean and preserve the spark plug and which shall supply 20 the priming fluid directly in the vicinity of the ignition spark. Another feature of my invention relates particularly to an improved means for feeding fuel to the cylinders at times when the throttle valve is 25 nearly closed, this feature being of especial benefit in connection with liquid fuels which are not readily vaporizable.

It is well known that on account of the difficulty of vaporizing the low grade fuels 30 now in use it is difficult, when the engine is cold, to supply a sufficient quantity of rich mixture in the vicinity of the ignition spark to ensure the ignition of the fuel charge, and as the available fuel for internal combustion engines becomes of lower and lower grade, this difficulty is aggravated.

It is well understood that once the fuel charge has actually been ignited it will burn or explode even if not uniformly mixed or 40 even if some of the fuel charge is unevaporated, due to the low temperature of the engine cylinder at the time of starting.

The deposit of carbon at the ignition point has heretofore been a source of much 45 trouble and this is becoming worse and worse as the grade of fuel drops.

The overheating of the porcelain insulators of the spark plugs is a present source of trouble and as low grade fuel results in 50 higher temperatures in the cylinders this trouble is also becoming worse.

Another difficulty resulting especially from fuel of low grade is that at times when the engine is throttled down or in other words idling there is not suction enough to 55 lift the low grade fuel as it is not vaporized

readily and consequently the engine "dies" or it has to be operated at a higher speed than is desirable.

By means of my invention I am enabled 60 to supply a rich mixture to the vicinity of the spark gap particularly when starting to preserve the spark plug from overheating, to prevent the production and lodgment of carbon upon the ignition points, and to effect 65 the delivery of fuel, especially low grade fuel, to the cylinders when the engine is idling, or in other words when the throttle valve is nearly closed. My invention results in many more important and desirable 70 results which will appear from the following description taken in conjunction with said accompanying drawings, in which—

Figure 1 is a fragmentary side elevation of an internal combustion engine, partly in 75 section, and illustrating one application of my invention;

Figure 2 is an enlarged vertical fragmentary section particularly illustrating my improved spark plug and connections. 80

Figure 3 is a fragmentary elevation partly in section particularly illustrating the collector in the intake;

Figure 4 is a vertical section of the engine intake particularly illustrating the fuel collector and vaporizer which I employ and its relation to the throttle valve and fuel feed nozzle of the carburetor; 85

Figure 5 is a view similar to Figure 1, illustrating the application of my invention for the purpose of feeding fuel to the engine when the engine is idling, and 90

Figure 6 is a fragmentary vertical section on the line 6—6 of Figure 5.

In said drawings 1 represents a multiple cylinder engine having an inlet manifold 2 provided with a central depending intake 3. The intake has a flange 4 at its lower end to which a carburetor 5 is secured. 95

The engine illustrated is a four-cylinder 100 engine and is provided with four spark plugs 6, one for each cylinder. The spark plugs are arranged in the top or cover plate 7 and the spark gap is at the upper end of the cylinder in accordance with the usual arrangement. The manifold 2 leads to two inlets or ports 8 which distribute the fuel gases to the four cylinders. 105

The carburetor 5 has a flange 9 at its upper end for securing it to the flange 4 on the intake and a throttle valve 10 is provided in the upper part of the carburetor to control 110

the flow of air and fuel to the engine through the intake.

The throttle valve 10 is rigidly mounted on a transverse shaft 11, rotatably mounted in the walls of the carburetor. The shaft has an arm 12 rigidly mounted on one outer end thereof which is adapted to be connected with any suitable control mechanism for manually setting the throttle valve. Space 10 below the throttle valve and carburetor is provided with a nozzle 13 through which liquid fuel is drawn by the suction of air through the intake of the engine.

With high grade gasoline or the lighter 15 fuel oils no special difficulty is experienced in lifting the fuel, emerging from the nozzle 13, with the air and delivering it through the manifold to the engine. But with the lower grade or heavier liquid fuel 20 which is now prevalent, it is practically impossible to lift all of the fuel emerging from the nozzle especially on wide open throttle when the suction is low and upon nearly closed throttle when the suction is 25 shut off from the region of the nozzle. Both of these conditions cause trouble and the difficulties due to both thereof are eliminated by my invention.

One especial trouble in the operation of 30 internal combustion engines at the present time is the difficulty of starting them in cold weather. This trouble results mainly from the fact that under low temperatures the present available fuel does not readily 35 vaporize and consequently the fuel which is fed to the cylinders falls to the lower part of the combustion space, viz, upon the cylinder head and away from the vicinity of the spark gap, consequently a very lean 40 mixture of air and fuel surrounds the ignition points, which lean mixture is difficult if not impossible to ignite. Furthermore, when the engine is idling the force of the suction at the fuel feed nozzle, while strong 45 enough to cause the fuel to emerge from the nozzle is not strong enough, on account of the nearly closed condition of the throttle at such time to pick up and lift the unevaporated fuel particles or drops. The 50 percentage of the present fuel which vaporizes readily is too small to afford a mixture which will ignite easily from an electric spark, consequently the throttle valve must be opened up farther than desired to 55 produce more suction with the result that the engine idles at too high a speed. All of these difficulties are eliminated by the use of my invention.

In the first place I provide a means for 60 collecting some of the unvaporized or rich mixture from the vicinity of the nozzle 13 and lifting it up and delivering it to a suction passage leading to the engine cylinders. In one form of the invention this 65 suction passage is the manifold and in an-

other form it is a passage which leads to the explosion spaces through the several spark plugs which I make hollow for this purpose. In both forms I deliver the rich mixture to the explosion space whereby I 70 am enabled to run the engine much slower when idling and in the hollow spark plug form I am enabled to cause the explosion of a much leaner mixture, as the rich mixture which I deliver at the spark plug readily ignites and when once ignited the balance of the charge though quite lean will 75 explode.

The spark plug 6 has an outer metallic sleeve member 14 which is adapted to be 80 screwed into a suitable threaded opening 15 provided in the cover plate 7. This sleeve is provided at its outer end with a threaded opening for receiving the threaded sleeve nut 16. The sleeve member 14 is 85 provided with an interior circumferential shoulder 17 opposed to the inner end of the sleeve nut and between which the annular rib 18 on an insulating sleeve member 19 is adapted to be clamped for holding 90 the insulating member in position. The insulating sleeve 19 stops short of the inner end of the sleeve member 14 forming a small chamber 20. Mounted in the insulation sleeve member 19, which is preferably made of porcelain or some similar material is a central metallic rod or stem 21 which forms one of the electrodes of the spark plug, the other electrode being formed by the inner end 22 of the sleeve 190 member 14. The inner end of the stem or rod 21 is slightly enlarged to form a shoulder 23 for contact with the inner end of the porcelain sleeve. The outer end of the rod 21 projects out beyond the outer end 105 of the porcelain sleeve and is threaded to receive a cap or nut member 24 which is provided with a petticoat 25 surrounding and protecting the outer end of the porcelain insulator sleeve. Preferably the stem 110 21 is formed in the porcelain sleeve when it is produced and the burning of the porcelain seals the stem in place and prevents the escape of gases through the porcelain sleeve around the stem.

I provide the inner end 22 of the sleeve member 14 with an internal flange 26 which has a central hole 27 slightly larger in diameter than the head 28 on the inner end of the stem 21. The annular space thus 120 formed between the head 28, which is long enough to project into the opening 26, forms the spark gap.

I provide the stem 21 with a central duct 29 leading from its upper end down through 125 the stem and ending between the ends of the head 28. At the lower end of the duct 29 it joins transversely radial ducts or minute passages 30 which lead into the chamber 20. These passages 30 are arranged 130

on two diameters at right angles to each other so that the fuel gases are delivered into the chamber 20 uniformly all around. It will now be understood that during the 5 suction stroke of the piston in the cylinder in which the spark plug is mounted that suction will be produced in the radial passages or ducts 30 and the central passage 29. The head 24 is provided with a central passage 31 which connects with a transverse passage 32 formed centrally in horizontal projections 33. The projections 33 of the several spark plugs are adapted to be jointed by short pieces of rubber tubing 34 and at one 10 point I arrange a T 35 for connecting the horizontal communicating passage thus formed with a collector of the unvaporized liquid fuel which I arrange in the intake between the nozzle 13 and the throttle 15 valve 10. The upper parts of the cap nuts 24 serve as binding posts for the wires 36 with which the spark plugs are connected with the ignition system of the engine. To prevent the escape of the gases in the cylinder through the several passages there is 20 a simple check valve provided at the upper end of each of the stems 21. This consists of a ball valve 37, which is adapted to seat upwardly to close the passage in the cap 25 30, which communicates with the horizontal passage 32. The ball is supported slightly below its closing position on a cross bar 38 mounted in the cap 24 so that it cannot fall and close the central passage in the stem 21. 35 For collecting the unvaporized fuel in the intake, I provide a wire gauze cylinder or tube 39 which I mount transversely in the intake or suction inlet just above the nozzle 13 or in other words between the 40 nozzle 13 and the throttle valve 10. This tubular collector is open at one end 40 and at the opposite end is fixed upon the inner end of the screw plug 41, adapted to be removably mounted in the wall of the intake 45 passage.

This plug 41 is provided with a central passage and is connected at its outer end to a small bore metallic tube 42 which connects at its other end with the lateral branch of the T 33. The ends of the tube 42 are connected or fastened by the usual compression couplings.

Upon the suction stroke of the piston a very strong suction is provided through 50 the central passage in the spark plug and the connecting passages and is effective to draw in a charge of the unvaporized fuel which has impinged and settled upon the wire gauze collector 39. Air is drawn in 55 with the fuel making a very rich mixture and this rich fuel mixture is distributed through the lateral passages or ducts 30 into the spaces 20 at the inner ends of the spark plugs from which it escapes 60 through the annular spark gaps, conse- quently this rich mixture is in the best position to be ignited by the ignition sparks and being ignited will cause the explosion of the rest of the charge even though the bulk of the charge be quite lean. It is evident 70 that upon each suction stroke of the engine regardless of the position of the throttle valve, whether open or nearly closed, that strong suction will be produced in the connecting pipe 42 and will tend to draw in a mixture and discharge the same into the explosion space of the engine and in the immediate vicinity of the spark gap. These gases are relatively cool as they flow through the passage of the spark plug and tend to cool the plug and prevent overheating of the electrodes and the porcelain insulator. As they are discharged into the chamber 20 with considerable force, they are violently intermingled and mixed and are heated sufficiently so that all of the fuel is thoroughly vaporized. The violent discharge of the gases serves another important function in that it tends to dislodge and blow out any carbon which may have 85 formed in or about the spark gap. I form the upper surface of the flange 26 conical or inclined to avoid any flattened surface upon which carbon may settle or remain.

As suggested hereinbefore the fuel which 90 is picked up by the collector 39 may be delivered to the cylinders through the manifold and in Figures 5 and 6 I have illustrated this form of my invention. In this form instead of the suction by-pass leading to the hollow 95 spark plug it is connected directly to the manifold 2. I provide a connector 43 having a threaded branch 44 for mounting in a suitable threaded opening provided in the side of the manifold and having a second branch 45 for connection to the pipe 42 by a compression coupling 46. Under some conditions it is desirable to admit additional air with the rich fuel mixture drawn through the tube 42 and for this purpose I provide the 100 connection 43 with an inlet port 47 normally closed by a spring pressed valve 48, which has a stem 49 slidably mounted in a guide hole 50 provided in a cap member 51 adjustably mounted in the connection 43. By adjusting the cap 51 the tension of the spring 105 can be regulated to control the admission of air through the port 47 as desired.

As explained the fuel which is drawn up through the pipe 42 is usually that which is 110 not easily vaporized under ordinary temperature, and while it will be delivered to the manifold even when the throttle is nearly closed, it may be in liquid form and will consequently not properly mix with the air. 115 To overcome this difficulty, I provide a heater to raise the temperature of the bypassed fuel. This heater consists of a closed box or chamber 52 surrounding a portion of the pipe 42 and adapted to be connected by a 120

125 130

4
5 pipe 53 with the exhaust manifold of the
6 engine and provided with a discharge pipe
7 54 at the opposite side of the chamber. It is
8 not thought necessary to illustrate the con-
9 nection of the pipe 53 with the exhaust
10 manifold. The pipe 42 is formed into sev-
11 eral loops or turns 55 to increase the heating
12 effect and is sufficient to raise the tempera-
13 ture of the fuel passing through the pipe 42
14 high enough to cause it to enter into the
15 manifold in gaseous form.

It will now be understood that in one aspect the invention comprises the extraction
15 of the unvaporized portion of the liquid fuel
from the intake passing it around the throttle
and back into the suction intake again
and during such bypassing applying heat to
vaporize it.

As many modifications of my invention
20 will readily suggest themselves to one skilled
in the art, I do not limit or confine my invention
to the specific structures herein shown
and described.

I claim:

25 1. In an internal combustion engine having
cylinders and a suction intake thereto,
a fuel feed nozzle in the intake, a throttle
valve between the nozzle and the cylinders
30 for controlling the suction, the cylinders
provided with inlet ports of small area at
their outer ends, ignition means arranged at
the inner ends of said ports, a fuel collecting
35 device arranged between the fuel feed
nozzle and the throttle, and a passage of
relatively small cross-sectional area con-
necting said fuel feed device with the outer
ends of said ports.

40 2. In an internal combustion engine having
cylinders and a suction intake thereto, a fuel
feed nozzle in the intake, a throttle valve be-
tween the nozzle and the cylinders for con-
trolling the suction, spark plugs for the cyl-
45 inders, said spark plugs having valve con-
trolled passages terminating at the spark
gap thereof, a fuel feed collecting device ar-
ranged between the nozzle and the throttle
in the intake and a passage of relatively
50 small cross sectional areas connecting said
fuel feed collection device with the outer
ends of the passages in the spark plugs.

3. In an internal combustion engine having
55 a cylinder, a spark plug arranged in the
outer end of the cylinder, the spark plug
provided with a central electrode which is
hollow, the outer end of said electrode con-
nected by a passage to the intake of the
55 engine, and means within the intake for feed-
ing a rich mixture through said passage.

4. In an internal combustion engine having
60 a cylinder and a suction intake, a spark
plug arranged in the outer end of the cyl-
inder, the spark plug provided with a central
electrode which is hollow, the outer end of
65 said electrode connected by a passage to the
intake of the engine, means for feeding a
rich fuel mixture to said passage, and a
check valve at the outer end of said electrode
to close said passage against pressure from
the cylinder.

5. In an internal combustion engine having
70 a suction intake, a throttle valve in the
intake, a cylinder, a spark plug for the cyl-
inder, the spark plug having a pair of elec-
trodes separated at their inner ends to form
75 a spark gap, one of said electrodes being
hollow and provided with outlet openings at
its inner end at the spark gap, the outer end
of the hollow electrode connected by a pas-
80 sage with the suction intake of the engine
beyond the throttle valve and means within
the intake for delivering a rich fuel mixture
thereto and a check valve for preventing the
subjecting of said passage to high pressures
within the cylinder.

6. In an internal combustion engine, a
85 cylinder, a suction intake for the cylinder, a
spark plug for the cylinder, the plug having
a central insulated electrode which has a
central passage, the inner end of said pas-
90 sage terminating at the gap of the spark
plug in a plurality of radially extending
outlets of small area, the outer end of said
passage connected to the engine intake and
provided with means for feeding a rich fuel
95 mixture to the cylinder.

In witness whereof, I hereunto subscribe
my name this 9th day of January, A. D.
1920.

WILLIAM F. PAGEL.
